FIG. 2.

FIG. 3.

FIG. 4.

UNITED STATES PATENT OFFICE.

WILLIAM J. GIBBONS, OF PHILADELPHIA, PENNSYLVANIA.

UPSETTING-DIE.

1,297,141.

Specification of Letters Patent.

Patented Mar. 11, 1919.

Application filed July 5, 1918. Serial No. 243,278.

To all whom it may concern:

Be it known that I, WILLIAM J. GIBBONS, a citizen of the United States, and a resident of the city of Philadelphia, county of Philadelphia, State of Pennsylvania, have invented certain new and useful Improvements in Upsetting-Dies, of which the following is a specification.

My invention relates to up-setting dies which are adapted for use in up-setting the opposite ends of lead or other metal bushings for armor plate and similar sheets of metal.

One of the objects of my invention is to provide means whereby the opposing dies may be readily and accurately centered with respect to each other.

Another object of my invention is to provide up-setting dies for up-setting relatively thick, heavy bushings of metal, such as lead, which are adapted to be operated manually.

A further object of my invention is to provide up-setting dies by the employment of which the opposing ends of short tubular sections of pipe may be expanded and turned laterally against the adjacent surrounding surfaces of the sides of the plate in the openings of which the bushings are secured.

Other objects and advantages of my invention will be particularly referred to and pointed out in the detailed description thereof which follows in this specification, or will be apparent from such description.

In order that my invention may be readily understood and fully comprehended and its practical advantages appreciated, reference may be had to the accompanying drawing in which I have illustrated two modified constructions of up-setting dies embodying my invention.

In the said drawing:

Figure 1 is a perspective view of one member of a pair of up-setting dies constructed in accordance with my invention;

Fig. 2 is a similar view of a die adapted for coöperation with the die shown in Fig. 1;

Fig. 3 is a view partly in longitudinal section and partly in side elevation of the two dies in working relation with respect to each other upon opposite sides of a plate and showing the same in opposing operative position after having been employed to

up-set the opposite ends of a bushing in an opening through said plate; and

Fig. 4 is a view similar to that shown in Fig. 3, of a modification, both dies, however, being shown in partial longitudinal section.

Referring to the drawing:—1 designates what may be described as the body of one member of an up-setting die having a working face or surface comprising a projection 2 rising from the central portion of a relatively wide surface 3. The surface of the projecting portion 2 is connected with the flat surface 3 by an inclined, annular, beveled surface portion 4. The die also comprises a handle or shank portion 5 which, when the dies are being used, is adapted to be held in the hands of an operator.

The inner or headed end of the die is provided with a central longitudinally extending centering opening 6, the outer surrounding edges of which are beveled as indicated at 7. The centering opening 6 is adapted to receive the centering pin 10 which projects from the end of a boss 11 which rises from the flat surface 12 of the head 14 of a coöperating die member. The boss 11 is connected or joined with the relatively large flat surface 12 by means of an annular inclined or beveled surface 15. The head 14 is provided with a handle or shank portion 17 similar to the handle 5 referred to and forming a part of the previously described die member.

In Fig. 4 the construction is the same as that illustrated in Figs. 1, 2 and 3, except that the bosses 2 and 11 are surrounded by annular grooves 20 which, in cross section, are semi-circular as shown. These grooves are formed in the relatively large flat surfaces 3 and 12. The outer surfaces of the bosses 2 and 11 in Fig. 4 merge into the semi-circular surface of the grooves 20, as is clearly shown. In both Figs. 3 and 4, 21 designates a plate having an opening 22 extending therethrough and 24 designates a bushing in said opening. Said bushing preferably consists of lead, although other suitable material may be employed to form such bushing. In forming the bushing, a section 105 of tube consisting of the material desired, such as lead, is placed in position over the projecting centering pin 10 and boss 11, and is then inserted through an opening 22. After having been so inserted, 110

the opposing coöperating die member is placed in position, with the boss 2 projecting into the projecting end of the tubular member or section which has been inserted 5 through the opening 22 in the plate 21 to the opposite side of the latter. It will be understood that the opposite ends of the section of tube or pipe are straight or square.

Having been thus positioned, the flat flanges 25 are formed as shown in Fig. 3, or the circular flange-like portions 26 are formed as shown in Fig. 4, by the application of force in any preferred manner to 10 the opposing die members. Such force may be applied by means of a hammer or mallet. When it is applied one of the die members should be held firmly in the hand, say the die member comprising the parts 1 and 5, 15 while by striking upon the outer end of the handle 17 with the hammer or mallet, the latter is driven against the directly opposing end of the section of tube which fits over the boss 11. Owing to the pressure exerted 20 against the opposing ends of the section of tube by means of the coöperating die head 1 the opposing ends of the section of tube are expanded to form either a flat flange as shown at 25 in Fig. 3, or a circular flange- 25 like portion as shown at 26 in Fig. 4. The 30 form or shape of the flange depends upon the character of the expanding surfaces of the coöperating up-setting dies. The form of bushing shown in Fig. 3 is known as a 35 half crown bushing, while that shown in Fig. 4 is known as a whole crown bushing.

The advantage of having a bushing of 40 relatively soft metal such as lead in an opening through a steel plate, the said bushing having rounded edges as shown in Figs. 3 and 4 of the drawings is that if it should be necessary to draw or pull a rope or cord or electric cable through the said opening such rope or cord or electric cable would 45 not be frayed or cut as it would be if it were drawn through the opening with the sharp corners as shown without the presence of the bushings of soft metal with rounded edges at the opposite ends of the opening 50 therethrough.

By reason of the presence of the centering opening 6 and the coöperating centering pin 10, the opposing coöperating up-setting parts 55 readily, quickly and accurately position and seat themselves with respect to each other in an opening which is being provided with a bushing as above described.

I claim:—

1. The combination of two up-setting dies, 60 one of which is provided with a central boss and a central centering opening and the other one of which is provided with a corresponding coöperating boss having a cen-

tering pin which projects from the center thereof and which is adapted to enter the 65 said centering opening, the said bosses being adapted to enter the opposite ends of a section of tube to up-set the opposite ends thereof.

2. Up-setting dies for forming bushings 70 of soft metal in openings through metal plate, the said dies each comprising a relatively large flat surface and a boss rising from said surface, the said large flat surface merging into the surface of said boss by an 75 inclined, curvilinear, annular surface, one of the said dies having a central centering opening and the other of said dies having a centering pin projecting from the center of its boss, said pin being adapted to enter the 80 said centering opening, substantially as described.

3. Up-setting dies adapted for the formation of bushings of relatively soft metal in 85 openings through plates of relatively hard material, the said dies each comprising a head having a handle or shank portion extending outwardly therefrom and each having a relatively large flat surface upon its inner end, and a boss rising from the center 90 of each of said surfaces, each of said dies being provided with an annular, inclined, curvilinear surface intermediate the said relatively large surface and the cylindrical 95 surface of the said bosses and one of the 100 said dies having a centering, longitudinally extending opening therein and the other of said dies having a centrally situated, inwardly extending centering pin adapted to enter the said centering opening, substantially as described.

4. In an up-setting die, the combination of two die members, each of which is provided at its inner operative end with inwardly projecting bosses adapted to enter 105 the opposite ends of a section of tube, one of the said dies being provided with a centering, longitudinally extending opening, terminating at its inner end in the center of the boss of the said die, and the other of said dies 110 being provided with a centering pin extending inwardly from the center of the boss of said die and the boss of each of said dies being provided with means at the base thereof for expanding and forming flanges upon 115 the opposite ends of said section of tube upon the application of force applied to said dies, which force is applied longitudinally thereof and in opposing directions, tending to cause the said dies to approach 120 each other.

In testimony that I claim the foregoing as my invention, I have hereunto signed my name this 28th day of June, 1918.

WILLIAM J. GIBBONS.
